UNITED STATES PATENT OFFICE.

LEWIS P. COOK, OF NEW YORK, N. Y.

DESIGN FOR A LOVING-CUP.

SPECIFICATION forming part of Design No. 28,732, dated May 31, 1898.

Application filed April 20, 1898. Serial No. 678,309. Term of patent 3½ years.

To all whom it may concern:

Be it known that I, LEWIS P. COOK, a citizen of the United States, residing at the city of New York, in the county and State of New

5 York, have invented and produced a new and original Design for Loving-Cups, of which the following is a specification, reference being had to the accompanying drawing, forming a part of my invention.

10 The figure is a side elevation of a loving-cup showing my design.

The leading or material features of my design are the ceramic vessel A, the handles B, of the same material as the vessel A, and a 15 band of contrasting material C at the top of

the vessel. The handles B are of the shape shown, the upper ends terminating in the scroll D and the lower ends in an enlarged or bell-shaped portion E.

What I claim is—

20 The design for a loving-cup as herein shown and described.

In testimony whereof I have signed my name to this specification in the presence of two subscribing witnesses.

LEWIS P. COOK.
